AUTOMOBILE JACK

Charles C. Craig, Morrill, Nebr.

Application December 23, 1943, Serial No. 515,442

4 Claims. (CL. 254—127)

1

This invention relates to and is primarily adapted for use in connection with automobiles, although capable of employment in various relations.

It is particularly aimed to provide a construction which is simple, durable, and relatively inexpensive, and capable of rapid operation merely through the manipulation of a lever.

Another object is to provide a construction wherein the parts are collapsible and capable of arrangement in very compact relation so as to occupy minimum space when not in use.

The more specific objects and advantages will become apparent from a consideration of the description following taken in connection with accompanying drawings illustrating an operative embodiment.

In said drawings:

Figure 1 is a view in side elevation showing the improved jack;

Figure 2 is a horizontal view taken on the line 2—2 of Figure 1;

Figure 3 is a vertical section taken on the plane of line 3—3 of Figure 2;

Figure 4 is a partial plan view showing an extension in place on the base;

Figure 5 is a vertical section taken on the line 5—5 of Figure 4; and

Figure 6 is a fragmentary longitudinal sectional view through a modified form of operating lever.

Referring specifically to the drawings wherein like reference characters designate like or similar parts, I provide a base 10 of any suitable length, dependent upon the particular automobile to be jacked and the operating space which accommodates such base. The base may be constructed of wood or any other preferred material, and along the top preferably has a metallic wear-plate 12 bolted or riveted thereto as at 13.

Elevating or lifting levers 14 and 15 are employed, preferably in pairs as shown, the same being pivotally connected together by a bolt 16 passing therethrough at suitable openings 17, a series of the latter preferably being employed to enable adjustment. Spacing the levers 14 apart and surrounding the bolt 16 is a sleeve 18 which is adapted for direct engagement with the part to be elevated, usually one of the suspension springs of the automobile as suggested at 19 in Figure 3.

The levers 15 are pivotally connected by a bolt 20 passing through suitable openings thereof, and one of a series of openings 21 provided through the base 10, to enable adjustment. Said levers 14 are connected by a bolt or rod as at 22 near their lower ends, and journaled thereon is a

2

sleeve or roller 23 adapted to travel along the wear-plate 12. It is particularly to be noted that levers 14 at their lower ends have guard extensions 24, below the roller 23, and at all times located below the upper surface of the wear-plate 12 and base 10.

A loop 25 extends rearwardly from the links or levers 14, preferably being pivotally connected thereto, and extending rearwardly from the loop 25 are a pair of draw elements 26 and 27, preferably in nature of metallic chains.

An operating lever is provided at 28, of any suitable construction, preferably detachable as shown. This lever may have a handle 29 as of wood with a pair of side plates 30 bolted thereto as at 31, and being spaced apart below such handle. In the space between the side plates 30 one or more hooks 32 are movable, being pivoted at 33 to the side plates by means of bolts, which are adjustable since a series of openings 34 are provided through the side plates for interchange thereof. Such side plates 30 have at their lower ends notches 35 whereby they may be engaged with and fulcrumed on a transverse pin 36 carried by the base 10 and crossing a slot or bifurcation 37 in one end thereof. The latter slot or bifurcation receives the lower end of the side plates 30 as shown in Figure 1 and enables operation thereof on the axis of the pin 36.

In operating the device the chain 26 is anchored at one of its links onto a preferred hook 32, and thereupon lever 28 is pulled to the right in Figure 1, thus drawing the lower ends of the levers 14 toward the operating lever, with roller 23 travelling on the wear-plate 12, and accordingly elevating the roller 18 and the spring 19 and the vehicle of which it forms a part. At the desired elevation for the roller 18 the other chain 27 is engaged with a hook 39 suitably fastened on the top of the base 10 at one side of the chain 26. With the parts thus held elevated through the engagement of the chain 27 with the hook 39, chain 26 may be released from the engaged hook 32 and the lever 28 moved to the left in Figure 1 and reengaged with a link of the chain 26 and the lever is again pulled to the right further to elevate the roller 18, if necessary. This operation may be repeated as many times as desired.

It will be understood that the lever 28 is detachable from the base by disengaging it at the notches 35 from the pin 36. In some instances a base longer than that shown will be advisable, in which event an extension base 40 is employed. This extension base has at 39' a hook equivalent to that at 39, and at 36' and 37' has a pin and

3

slot or bifurcation equivalent to those at 36 and 37, so that when the extension is in place the lever 28 may be engaged with the pin 36' and be actuated in cooperation with chains 26 and 27 as when engaged with the pin 26. In order separably to connect the extension 40 in line with the extension 10 as shown in Figure 4 metallic straps 41 and 42 are bolted or riveted as at 43 to the lower and upper surfaces of the extension, and they extend rearwardly beyond such extension, being riveted together as at 44. Strap 42 preferably has a depression or loop at 45 and a tongue at 46, the tongue being insertable into the bifurcation 37 beneath the pin 36 and then into overlapping engagement with the upper surface of base 10 as shown in Figures 4 and 5, with the pin 36 engaged in the depression 45.

As previously intimated, I may use an operating lever such as 28 with but a single hook like that employed at 32. Such a modified form of lever is shown in Figure 6. It has a handle, for instance of wood, at 29' bolted at 31' to a pair of side plates 30' having notches 35' in their lower edges for engagement with either pin 36 or 36'. The single hook is shown at 32' for accommodation in the space between the side plates 39' and to which it is pivoted by a bolt at 33'.

Various changes may be resorted to provided that they fall within the spirit and scope of the invention.

I claim as my invention:

1. A jack of the class described comprising an elongated base, a lever pivoted to the base, a lever pivoted to the first-mentioned lever above the base, means carried by the second-mentioned lever to travel along the base, and means associated with the base operable to draw the second-mentioned lever toward the fulcrum of the first-mentioned lever to elevate them at their junction, and guard means on the second-mentioned lever extending therefrom below the upper surface of the base, said means on the second-mentioned lever movable on the base being a roller, a wear-plate on the base along which the roller moves, said means to actuate the levers consisting of a pair of draw elements extending from the second-mentioned lever, an operating lever on the

4

base having hook means engageable with one of the draw elements, and an anchoring hook on the base engageable by the other draw element.

2. A jack of the class described comprising an elongated base, a lever pivoted to the base, a lever pivoted to the first-mentioned lever above the base, means carried by the second-mentioned lever to travel along the base, and means associated with the base operable to draw the second-mentioned lever toward the fulcrum of the first-mentioned lever to elevate them at their junction, and guard means on the second-mentioned lever extending therefrom below the upper surface of the base, said means on the second-mentioned lever movable on the base being a roller, a wear-plate on the base along which the roller moves, said means to actuate the levers consisting of a pair of draw elements extending from the second-mentioned lever, an operating lever on the base having hook means engageable with one of the draw elements, and an anchoring hook on the base engageable by the other draw element, said base having a slot, a pin crossing the slot, and said operating lever extending into the slot and having a notch engageable with said pin.

3. A structure of the class described having a base, jacking means thereon including an operating lever, said base having a slot and a pin crossing said slot, said operating lever having a notch whereby it may extend into the slot and fulcrum on said pin, and an extension base also having a similar notch and pin to accommodate said operating lever, said extension at one end having a strap provided with a depression to receive the adjacent pin, said strap being of a length to engage the upper surface of the base.

4. A structure of the class described having a base, jacking means thereon including an operating lever, said base having a transverse pin, said operating lever having a notch whereby it may fulcrum on said pin, and an extension base also having a transverse pin to accommodate said operating lever, and means at one end of said extension provided with a depression for coupling engagement with the first transverse pin.

CHARLES C. CRAIG.
